UNITED STATES PATENT OFFICE.

WILLIAM J. NEWTON, OF LYNBROOK, NEW YORK, ASSIGNOR, BY MESNE ASSIGNMENTS, TO JOHN G. LIVINGSTON, OF WOODMERE, LONG ISLAND, NEW YORK.

SWITCH OR RECEPTACLE BOX.

1,386,421.

Specification of Letters Patent. Patented Aug. 2, 1921.

Application filed March 9, 1916. Serial No. 83,086.

To all whom it may concern:

Be it known that I, WILLIAM J. NEWTON, a citizen of the United States, and a resident of the village of Lynbrook, county of Nassau of the State of New York, have invented certain new and useful Improvements in Switch or Receptacle Boxes, of which the following is a description.

My invention relates to boxes or containers for electric switches, base receptacles, and the like, and is particularly directed to the means for securing said boxes in position.

One of the most frequently experienced difficulties in the installation of electric wiring in buildings is due to the fact that the outlet boxes which are usually installed prior to the application of plaster, baseboards, or other wall covering, are inaccurately set with respect to the face of the finished wall. As a result, the portion of the outlet box to which the switch or receptacle box is to be attached is so located relatively to the finished surface that it is impossible, by the use of the ordinary attaching means alone, to firmly secure the switch or receptacle box thereto in such position that the top of the latter will be flush with the finished wall surface.

Switch boxes and receptacle boxes as generally constructed are provided with a pair of stationary lugs flush with the top thereof. Set screws are passed through holes in these lugs into threaded holes in the outlet box cover to retain the switch or receptacle box in position within the outlet box cover. Obviously, if the top of the outlet box cover lies below the wall surface, the switch or receptacle box cannot be firmly held in position flush with the wall surface by the set screws, unless washers or the tubular spacing members be mounted on the set screws between the lugs and the outlet box cover. It has accordingly been common practice, in the art, to employ such washers or tubular spacing members, with the result that the time consumed in properly positioning the switch or receptacle boxes has been excessive, and the results have, at best, been inaccurate. In order to avoid the extra expense of time and material involved in the use of these spacing members, wiremen sometimes simply omit them and rely solely upon the face plate for retaining the switch or receptacle box in position. This careless

method of supporting the switch boxes is, of course, very unsatisfactory, since the vibration of the buildings will often dislodge a switch or receptacle so supported, sometimes to such an extent as to disconnect the contacts from the binding posts.

In carrying out my invention I provide means whereby the switch or receptacle boxes may be accurately and firmly secured in proper position in much less time than has been required heretofore, and without the aid of any spacing or similar members, irrespective of the position of the outlet box cover with relation to the finished wall surface.

I make provision also for a slight angular adjustment of the switch or receptacle box with respect to the outlet box, so that the switch or receptacle box may be straight even though the outlet box is tilted slightly.

Referring to the drawings, Figure 1 shows a perspective view of a switch or receptacle box constructed in accordance with my invention.

Fig. 2 is a sectional view of a switch box, such as that illustrated in Fig. 1, together with its attaching and positioning means.

Fig. 3 is a top view of Fig. 2.

Fig. 4 is a view similar to Fig. 2, but showing a modified form of attaching and supporting means.

Fig. 5 is a detailed sectional view of one of the supporting lugs shown in Fig. 4, and Fig. 6 is a plan view thereof.

The box or container 10 shown in Fig. 1, may be of any desired form, depending upon the use to which it is to be put, and may be made of any suitable material, such as porcelain or other insulating material. In the end walls of box 10, there are provided one or more longitudinally extending slots or recesses 11. These recesses do not extend to the full depth of the box, but terminate in abutments 12 having apertures 13. Abutments 12 may be flush with the ends of the box, as illustrated in Fig. 1, or may be of any desired form, provided they are either integral with box 10 or firmly secured thereto.

In the embodiment of my invention, shown in Fig. 2, the bridge plate 14 of the switch extends over recesses 11, and is fastened to box 10 by means of screws 15, or any other suitable means. In each portion or ear of bridge plate 14, which extends

over recess 11, there is provided an aperture 16 adapted to hold one end of the adjusting screw 17, the other end of which is held in the aperture 13 of abutment 12. In 5 order that it may not be necessary to make a hole of accurate size in abutment 12, and in order to reinforce the abutments, I may apply metallic washers at the opposite ends of the abutment. As shown herein, the 10 washers take the form of a U-shaped metallic piece 18, surrounding the abutment and having two apertures, through which the adjusting screw passes. In this embodiment of my invention the adjusting screws 15 are provided at the top and at the bottom with shoulders which contact respectively with the underside of bridge plate 14, and the upper washer of the member 18, so that the adjusting screws are held firmly against 20 longitudinal movement with respect to the switch box, but at the same time are permitted to turn.

Mounted upon the adjusting screw 17, and in threaded engagement therewith are 25 lugs 19, the inner ends of which are shaped to conform to the shape of the longitudinal recesses 11. The outer ends of lugs 19 are provided with slots through which attaching screws 20 may be passed for the pur- 30 pose of fastening the lugs to the outlet box, or other support 21. The slots in the outer ends of the lug 19 permit the switch box to be turned slightly to bring the face plate into the desired position.

35 In the modified embodiment of my invention shown in Fig. 4, the bridge plate 14 terminates inside of longitudinal recesses 11. These recesses terminate in abutments 12, as in the modification of Fig. 2 and me- 40 tallic washers or U shaped pieces 18^a are also provided. The U shaped pieces 18^a of Fig. 4 differ from the U shaped pieces 18 of Fig. 2, in that instead of being provided with plain apertures, their apertures are 45 threaded to take the adjusting screw 17^a. Lugs 19^a of Fig. 4 have inner ends con- forming to the shape of the longitudinal recesses of 11 and are mounted upon ad- justing screws 17^a, as shown in Figs. 5 and 50 6, wherein it is shown that lugs 19^a have a large aperture 22 permitting the head of adjusting screw 17^a to pass therethrough, and a smaller aperture 23 which communi- cates with aperture 22, so that the reduced 55 portion of screw 17^a may be passed into aperture 23 when adjusting screw 17^a has been backed off sufficiently to permit lug 19^a to clear the top of switch box 10. When the screw 17^a is then advanced so that the 60 lug is guided in the recess 11, the walls of the recess prevent the disengagement of the small aperture 23 from the reduced portion

of the screw 17^a, and the lug is thus held against longitudinal movement with respect to the screw.

65 The operation of either modification of my invention is generally as follows:

The outlet box 21 is placed in position. The switch box is then attached to the outlet box by means of screws 20, and its proper 70 angular position adjusted by means of the slots in the outer ends of lugs 19 and 19^a. If line P. L. of Figs. 2 and 4 is the plaster line or line of the finished wall, the adjusting screws 17 or 17^a are then turned by 75 means of a screw driver until the outer surface of the bridge plate 14 is brought flush with the plaster line. In the embodiment shown in Fig. 2 the turning of screws 17 causes the lugs 20 to move along the screw 80 17, and the screw 17 being fixed against longitudinal motion, the switch box 10 is thus moved in or out as desired. In the modification shown in Fig. 4, the turning of the adjusting screw 17^a causes the adjusting 85 screw to be screwed into the member 18^a, and the lug 19^a being prevented from longitudinal movement upon adjusting screw 17^a, the switch box is moved in or out as desired.

90 I do not intend to confine myself to any particular form of my invention since it will be obvious that it may be greatly modified without departing from its spirit. Thus the form of the lugs or the mechanism for 95 adjusting the same may be greatly changed. Also the longitudinal recesses may be greatly modified since they constitute guiding and holding means only for the lugs, and need, therefore, be of no particular 100 shape; in fact they may take any suitable form which will properly perform the guiding and holding function.

95 What I claim is:

A device of the kind described comprising 105 a box provided with a longitudinal recess, a lug slidably mounted within the recess, a bridge member secured to the top of said box and provided with an apertured ear overlying one end of said recess, an aper- 110 tured abutment overlying the other end of said recess, and a screw rotatably mounted in the recess in the threaded engagement with the lug for adjusting the lug longitudinally of the recess, said screw being pro- 115 vided with unthreaded ends mounted in the apertures of the ear and the abutment, and with shoulders co-operating with said ear and abutment to retain said screw against longitudinal movement.

120 In testimony whereof I have signed this specification.

WILLIAM J. NEWTON.
